(57) **CLAIM**

The ornamental design for a retractable pet leash as shown and described.

DESCRIPTION

FIG. 1 is a right side view of a retractable pet leash showing my new design;

FIG. 2 is a left side view thereof;

FIG. 3 is a right, front perspective view thereof;

FIG. 4 is a left, front perspective view thereof;

FIG. 5 is a left, rear perspective view thereof;

FIG. 6 is a right, rear perspective view thereof;

FIG. 7 is a front view thereof;

FIG. 8 is a rear view thereof;

FIG. 9 is a top view thereof; and,

FIG. 10 is a bottom view thereof.

The broken lines depicting portions of the retractable pet leash form no part of the claimed design.

1 Claim, 10 Drawing Sheets
